COMBINATION ICE MAKING MACHINE AND STORAGE CABINET OR THE LIKE

Herbert L. Smith, Van Nuys, Calif., assignor to S. Jerome Tamkin, doing business as Phillips Manufacturing Co., Los Angeles, Calif.

Filed May 8, 1961, Ser. No. 65,072

Term of patent 14 years

(Cl. D67—3)

FIG. 1 is a front perspective view of a combination ice making machine and storage cabinet showing my new design;

FIG. 2 is a top view thereof;

FIG. 3 is a right side view thereof; and

FIG. 4 is a bottom view thereof.

The rear not shown is plain.

I claim:

The ornamental design for a combination ice making machine and storage cabinet or the like, substantially as shown and described.
